THE NORRIS PETERS CO., PHOTO-LITHO., WASHINGTON, D. C.

UNITED STATES PATENT OFFICE.

AUGUST LAMMEDEE, OF SOUTH BEND, INDIANA.

STRAW-STACKER.

SPECIFICATION forming part of Letters Patent No. 430,863, dated June 24, 1890.

Application filed August 7, 1889. Serial No. 320,010. (No model.)

To all whom it may concern:

Be it known that I, AUGUST LAMMEDEE, of South Bend, in the county of St. Joseph and State of Indiana, have invented certain new and useful Improvements in Straw-Stackers; and I do hereby declare that the following is a full, clear, and exact description thereof, reference being had to the accompanying drawings, and to the letters of reference marked thereon, which form part of this specification, in which—

Figure 1 is a side elevation of my improved straw-stacking machine, parts of the carrier-belt-operating mechanism being omitted and broken away, as this invention relates principally to the means for vibrating or oscillating these carrier-belt frames laterally. Fig. 2 is a plan view of the operating mechanism for intermittently moving the carrier-frames laterally. Fig. 3 is a detail cross-sectional view through the annulus supporting the carrier-frame. Figs. 4 and 5 are side views in detail of the carrier-belt frames, showing my improved device for opening or unfolding 20 and folding the sections thereof. Fig. 6 is a detail sectional end view of the devices shown in Fig. 11, looking in the direction shown by the arrow on said figure. Figs. 7, 8, 9, and 10 are detail views. Fig. 11 is a detail plan 25 view, enlarged, of the tripping or quick-throw mechanism of the pivoted frame. Fig. 12 is a detail view of the levers X and Y and connections.

This invention is an improvement in straw 35 stackers and carriers such as are shown and described in my Letters Patent No. 385,634, dated July 3, 1888; and the object of the present invention is to improve the devices for imparting a lateral vibration to the carrier-belt 40 frames automatically; and the invention consists in the novel construction and arrangement of parts hereinafter described and claimed.

Referring to the accompanying drawings 45 by letter, A designates a frame, which may be mounted on a wagon-body or provided with wheels (not shown) for transportation. Upon this frame is supported an annulus V, hereinafter described, and upon said annulus 50 is supported a frame Z, constructed substantially as shown and described in my aforesaid patent, or in other suitable manner.

Upon frame Z are supported two belt-carrying frame-sections Z² Z³, the latter being hinged at one end to the former and the former being supported on frame Z by four hinged bars Z⁴ at the corners thereof, as described in my said patent. Section Z³ is adapted to be folded on section Z² during transportation, and to facilitate the folding and unfolding thereof I attach arms Z⁵ Z⁶ to the side bars of section Z³ at the hinged end thereof. When unfolded, the arms lie alongside of section Z², as shown in Fig. 4, and when folded they extend, as shown in Fig. 5. To fold section Z³ these arms or handles Z⁵ are pulled down, thus raising the outer end of section Z³ and turning it toward Z² until it passes the center of gravity and falls upon frame Z², and to unfold the handles are depressed until the section Z³ again passes the center of gravity, moving in an opposite direction, and falls outward. The extreme end of section Z³ is usually up in the air, and it is, as ordinarily mounted, extremely difficult to fold and unfold; but these handles enable the operator to quickly and simply manipulate the sections.

B designates a horizontal shaft journaled transversely of frame A, at one end thereof, in suitable bearings in or attached to the side bars A' A', and a is a pulley on the outer end of said shaft, by which motion can be transmitted thereto from a suitable engine by belting. (Not shown.)

V designates an annulus or ring, preferably of metal and of large diameter, being about equal in diameter to the width of the frame, and said annulus is supported directly over shaft B upon rollers b b, attached to frame A.

V³ is an annular depending flange on the inner periphery of annulus V, against which abut studs or lugs V⁴, secured at regular intervals on frame A in such position that the annulus is centered and retained thereon. These lugs preferably have rollers V⁶ in their ends to reduce friction between them and flange V³.

V⁷ designates a bar supported upon and diametrically of annulus V, and V² is a short vertical shaft attached centrally to said bar and having a bevel-gear on its lower end meshing with a bevel-gear C on shaft B, and

also having a gear F on its upper end meshing with a gear G on a short shaft g , journaled in the frame Z, and having a sprocket-wheel H, by which and suitable belts motion can be transmitted to the carrier-belts. The perimeter of annulus V is provided with sprocket-teeth v , as shown, and it has a series of perforations $v' v'$ for the engagement of adjustable pins $j j'$. (Hereinafter referred to.)

10 t designates a vertical shaft journaled in proper bearings in cross-pieces $A^2 A^4$ of frame A, at the end thereof, opposite shaft B, and S is a large worm-gear loosely mounted on said shaft and having a stud S' on its upper face, which is engaged by a horizontal arm or pin S'' on shaft t.

15 T is a sprocket-wheel loosely mounted on the upper end of shaft t, having a stud or pin T', adapted to be engaged by a pin T'' on shaft t, as indicated, to rotate the wheel with the shaft. Preferably both wheel T and gear S have two or more holes in their webs, and instead of casting studs thereon I employ adjustable pins, as shown, by which the 20 amount of movement of shaft t independently of the gear or pinion can be regulated.

P designates a rectangular frame lying parallel with gear S and transversely of frame A, being pivoted at one end, as at P', to frame A, 25 its opposite or free end being permitted to oscillate or vibrate.

r and q are two shafts journaled longitudinally of frame P in suitable bearings, and on opposite sides of and in the same plane 30 as gear S.

R and Q are worm-gears on said shafts, either of which can be brought into engagement with gear S by swinging the free end of the frame P laterally.

40 m and n are sprocket-wheels on said shafts, and K is a sprocket-chain running over both said gears and transmitting motion thereto from a sprocket-wheel D on shaft B, as indicated in the drawings. The sprockets m and n are at the pivoted end of the frame, so that lateral movement thereof will not disengage chain K therefrom. The free end of frame P is supported on frame A, so that it can move laterally, and it has two projecting arms $P^3 P^3$, one of which is engaged by a 45 spring-catch L, secured to cross-piece A^2 of the frame A, by which frame P, after shifting, is held until forcibly shifted again.

Y designates a lever pivoted at one end on a cross-piece A^2 of frame A above frame P, and extending outwardly over and between arms P^3 , on which are mounted a pair of lugs Y' Y'', rising from a strap or bar Y'', against which lugs lever Y is alternately thrown. The outer 55 end of said lever Y is pivotally connected to one end of a rod X, the inner end of which is supported in a U-shaped bracket X', pivotally secured on cross-piece A^2 , and to said rod is attached a coiled spring X'', which bears 60 against a pin y^4 on rod X and against one end of the bracket and pulls said rod inward. Owing to the different pivotal points of at-

tachment of lever Y and bracket X' to the bar A^2 , when the lever Y is pulled forward or backward until the point of attachment of lever Y and rod X is in line with the pivotal points of attachment of said lever and rod to bar A^2 , spring X'' will be tensioned.

W designates a sliding bar lying longitudinally in frame A and below annulus V, and having an upstanding lug W², which is adapted to be engaged by depending pins $j' j'$ of said annulus. The front end of the bar is loosely connected by a slotted plate W' and a pin to lever Y. A sprocket-chain u transmits motion from wheel T to annulus V.

The operation is as follows: The arc of movement of the carrier-frame Z is determined and regulated by the pins $j j'$, which are set closer to or farther from each other, as a long or short vibration of the frame is desired. Motion being imparted to shaft B and the frame P shifted to engage worm Q with gear S, annulus V will turn in one direction until pin j strikes W². Bar W will then be drawn forward, pulling lever Y toward the annulus until it passes a line coincident with the pivots of bracket X' and lever Y, when the spring X'', which has been tensioned by such movement, will pull Y quickly and violently over, making it strike against the opposite lug Y' and shift frame P laterally, causing it to disengage worm Q from gear S and to engage worm R therewith. This will stop the motion of annulus V and frame Z and the motion of gear S will be reversed. Pin S' will leave S'', and shaft t will remain at a standstill until S has revolved sufficiently to engage another stud S'' on the opposite side of the single stud, when a reverse movement is imparted to shaft t. Sprocket T still remains idle until the shaft t has brought pin T'' into engagement with the stud on said sprocket, when said sprocket is turned and a reverse movement imparted to annulus V and frame Z. The annulus will continue to revolve until pin j' strikes W² and throws lever Y, and hence frame P, back to its first position, when (after the parts have remained stationary for a few moments during the reversing of the shaft and gears) movement is imparted to annulus V in the opposite direction. Motion is imparted from sprocket H by a chain H' to a shaft H², carrying sprockets H³, which transmit motion by chains H⁴ to the carrier-belt wheels H⁵ of the carrier-belts H⁶ on frames Z² Z³.

By properly proportioning—that is, enlarging—gear S a sufficient pause might be obtained at the end of each lateral vibration of frame P; but by employing the pins or lugs and loosely mounting sprocket T, as described, the intervals between the movements of the annulus are increased without enlarging the parts to an awkward degree. By using several holes in the sprocket and gear and adjustable pins the interval can be varied, or by projecting pins S' and T' through shaft t the intervals will be shortened, as the shaft and

gear will only have one-half revolution before engaging.

Having thus described my invention, I claim—

- 5 1. The combination of the main frame, the revolving annulus mounted thereon and supporting the carrier-belts and their frames, with the vertical shaft, a worm-gear, a laterally-movable frame embracing said gear and having two worm-shafts on its opposite sides, the devices for transmitting motion from said shaft to the annulus, and the spring-operated lever-reciprocating bar, and connections, substantially as described, for automatically shifting said movable frame, substantially as specified.
- 10 2. The combination, with the revoluble annulus and the carrier-belt frames supported thereon, and the adjustable pins on said annulus, of the vertical shaft carrying a loose worm-gear and sprocket-wheel, and a laterally-movable pivoted frame having two worm-shafts adapted to respectively engage said worm-gear when the frame is shifted, the spring-controlled lever pivoted on the main frame and engaging studs on said movable frame, the movable bar engaging said lever and actuated by the pins of the annulus, and the sprocket-wheels and chains, constructed
- 15 30 and arranged substantially as specified.
3. The combination of the shaft *t*, the gear *S* thereon, having pins *S'* and the pin *S²* on said shaft, and the laterally-movable frame *P* and worms *Q* and *R* thereon, with the annulus

V, supporting the carrier-belt frames and the devices for driving the annulus from said shaft, and the means, substantially as described, for automatically shifting said frame from the annulus, all substantially as and for the purpose described.

4. The combination of the vertical shaft *t*, gear *S*, and the connections between said shaft and the revoluble support of the carrier-belt frames, with the lever *Y*, mounted on the main frame and engaging stop-lugs on said movable frame, the spring-controlled rod *X*, attached to said lever, and the longitudinally-movable bar *W*, all substantially as and for the purpose described.

5. The combination of the annulus *V*, having pins *j j'* and supporting the carrier-belt frames, with the vertical shaft *t*, the sprocket and worm wheels loosely mounted thereon, the movable frame *P*, the worms *Q* and *R*, supported thereon, the sprockets and chains for driving said worms, the locking-latch *L*, and devices, substantially as described, for automatically shifting said frame from the annulus, all substantially as and for the purpose described.

In testimony that I claim the foregoing as my own I affix my signature in presence of two witnesses.

AUGUST LAMMEDEE.
